I S^{an} M^o Techam^s Design for a Stove
No 39.

Patented Oct. 10, 1845

6th Sept. 1845

Dec. 39

John S. Pickham & Merritt Pickham Utica, New York.
Letters Patent (Design No. 39) Dated 10th October 1841.
(Antedated 6th Sept. 1845).

The schedule referred to in these Letters Patent and making
part of the same

To all whom it may concern Be it known that we John S
Pickham and Merritt Pickham of the City of Utica County of Oneida
& State of New York by our industry genius, & expense have invented and
produced a new and original design, shape configuration and pattern
of stone plates to be used in the manufacture of stoves

The nature of our invention consists in the peculiar shape,
configuration, and ornamental carved work of the outer surface of
the cast-iron plates forming the stove. The stove is in the form of an

elevated box stone of cast iron.

The outer surface of the front & back plates consists of figures representing vegetation flowers fruit two human figures two hours of plenty a badge with the names of the Paleontes and a variety of fanciful carved figure work at the bottom of the plate are leaves representing vegetation spreading and running towards the edges of the plates in the center of which and on the center of Plates is a figure representing a flower in profile directly above the flower are two flower buds one at the right & one at the left hand sides over these two buds and nearly resting upon their points is a full blown rose, on the right and left of this rose and elevated a little above it are two full blown morning glories between which and above the rose and running further up the plate than the morning glories is projected the delineation of six rosettes upon the right & left sides of the plates are delineated two human forms representing two boys each dressed in high ornamental sandals and a loose frock dress with full length sleeves the dress ornamented and with an ornamental border below the waist and around the bottom of the skirt, the collar turning down around the neck and decorated with worked figures, and fastened around the neck with a cord and tassels, each figure wears a heavy sash about the waist, and a mantilla shawl or light cloak thrown loosely over one arm and is represented bare headed, and with a pointed nose.

The two figures join the fingers of the inner right and left hand of each and sustain upon the thumbs by means of a cord passing through a ring a circular ornamented body between them on the center of the plate bearing engraved upon it the following inscription J. S. & M. Peckham Utica Patented 1845. These figures hold in the outer right & left hand, by the small end an ornate hem of Plenty from each of which is seen falling fruit & nuts &c. Above the human figures and upon the upper portion of the plate is upon each bunches of grapes muskmelons pears apples plums

leaves of grape vine and other ornamental work

The front and back plate entirely resemble each other except that the flue or pipe is placed in the back plate the top and end plates are covered with fanciful ornamental carved work which is not capable of a more particular description the door which is in the right-hand end plate is ornamented with a stem or sprig with numerous fancy leaves & flowers. the box is capped or topped with a close urn made of cast iron plates representing a flower & fruit basket; with a handle at each side this basket is represented by figures on the outer surface of the plates as containing various kind of fruit and flowers among which are the Pear, the quince, the Plum, and the grapes.

The box stands upon a circular oblong cast iron hearth plate, the outer edge of which is decorated with an ornamental border three inches in width within a bead or rounded moulding, upon which border is represented full blown roses, rose leaves, morning glories, and other fanciful flowers, and leaves, and also bunches of grapes, the border within the moulding is three & a half inches in width along the front view or side of the stone running ^{more} to a point, becoming narrower and turning into the box at the back side of the stone instead of extending entirely around the outer edge of the plate upon the upper surface of the hearth plate surrounds the lower part or bottom of the box where it rests upon the hearth plate and forming a groove within which the lower end of the upright plates of the stone are held is a raised fancy carved ornamental border incapable of more particular description.

The stone rests on four feet or legs the outer surface of which is ornamented with carved lines embossed carved work grapes, leaves of the vine and other small ornamental figures which cannot be more fully described.

The whole is raised or embossed figures upon the outer surface of the cast iron plates

Des. 39

4

The above description is as perfect as we are able to make reference being had to the accompanying drawing.

What we claim as our invention and desire to secure by Letters Patent is the design, shape, configuration, style and ornamental carvings of the external surface of the plates of the stones.
